UNITED STATES PATENT OFFICE.

JOHN E. ERICKSON, OF ROCKFORD, ILLINOIS.

RATCHET WRENCH.

Application filed February 26, 1923. Serial No. 621,274.

To all whom it may concern:

Be it known that I, JOHN E. ERICKSON, a citizen of the United States, residing at Rockford, in the county of Winnebago and State of Illinois, have invented certain new and useful Improvements in Ratchet Wrenches, of which the following is a specification.

This invention relates to tools, and more particularly to wrenches of the type known as ratchet head wrenches.

The primary object of my invention is to provide an improved wrench of this type characterized by its simplicity and durability of construction, and its adaptation as a socket for a spanner wrench to a wide range of bolt heads or other objects to be turned.

In furtherance of the foregoing, my invention aims to provide a wrench-head having a spindle rotatable in a handle and adapted to be removably retained in operative position thereon, and ratchet teeth at the base of the spindle adapted to be engaged by a sliding reversible pawl of novel construction permitting use of a series of wrench-heads of different sizes.

Another feature is the construction of the wrench-head spindles and ratchet-teeth of uniform dimensions and shaping of the handle so that its spindle-carrying end is of an outside dimension substantially equal to that of the smallest wrench-head, thus allowing the wrench to be used in close corners. With the smallest wrench-head for small nuts, bolts, etc., and at the same time possessing ample strength for the larger sizes of wrench-heads.

A further object resides in the provision of a wrench construction of the character described including an extension shank for use with the handle at a distance from the wrench-head.

Other objects and attendant advantages will be appreciated by those skilled in this art as the invention becomes better understood by reference to the following description when considered in connection with the accompanying drawing, in which—

50. Figure 1 is a side elevation of a ratchet wrench embodying my invention;

Fig. 2 is a top view of the wrench;

Fig. 3 is a longitudinal section taken on the line 3—3 of Fig. 2;

55. Fig. 4 is a cross-sectional view taken on the line 4—4 of Fig. 3;

Figs. 5 to 8 inclusive are top views of a series of wrench-heads of different sizes;

Figs. 9 to 12 inclusive are side views of said wrench-heads;

Fig. 13 is a side view of an extension shank embraced by my invention; and

Figs. 14 and 15 are views of the top and bottom ends, respectively, of said extension shank.

The wrench head designated generally by 16, is preferably cylindrical and formed with a socket 17 in one end shaped to receive a nut or the like. This end of the wrench-head may also be of the spanner type. The opposite end of said head is machined by turning, to provide a spindle 18, and has radial, parallel-side recesses 19 emanating from the spindle and forming ratchet teeth 21. The spindle 18 has an annular groove 75 22 for the reception of a retaining element 23 for the prevention of a retaining element which will be presently described.

The head 23 of a handle 24 is bored at 25 and 26, the former bore being for the reception of the wrench-head shank 18, and the latter for a cylindrical pawl 27. The handle-head carries a spring-pressed ball 28 urged into the groove 22 for preventing displacement of the spindle from lengthwise movement in the handle-head, but permitting rotation of the wrench-head on the handle and removal of the latter from the former by pressure sufficient to overcome the spring pressure. When in the operative relation shown in Figs. 1 to 4 inclusive, the underside of the handle-head bears against the adjacent end of the wrench-head, providing bearing between said parts additional to that on the spindle.

The pawl 27 has at one end an elongated, 95 diametrically disposed tooth 29 having a ratchet-tooth engaging face 31 and a beveled or curved face 32, the former being adapted for driving the wrench-head and the latter for riding over the ratchet teeth when 100 backing the handle on the wrench-head. The opposite end of the pawl has a diametrical ridge 33 against which bears the end 34 of a flat spring 35, secured by a screw 36 to the handle, said end 34 being shaped 105 to fit said pawl end 33 for holding the pawl against rotative movement from an operative position. The pawl may be reversed by swinging a projecting pawl finger 37 180 degrees in a clockwise direction viewing Fig. 110 2, and vice versa, without removing the pawl or spring. It will be manifest from the

foregoing that a ratchet-wrench is provided, the wrench-head of which may be rotated in reverse directions controlled by the placement of the pawl 27.

5 My invention also contemplates the provision of a series of wrench-heads of different diameters, a number of which are shown in Figs. 5 to 8 inclusive, including the smallest and largest of this particular set. 10 The sockets in these heads are correspondingly graduated in size. The dimensions of the spindles 18 and of the ratchet recesses 19 are, however, uniform, so that any wrench-head fits the one end and its pawl. 15 One of the features of my invention in this regard is that the sides 38 of the handle-head 23 are substantially parallel and the end 39 of said head is semi-cylindrical, the radius thereof being substantially equal and 20 at least not appreciably greater than that of the smallest wrench-head 16' shown in Figs. 5 and 9. This allows the wrench to be used on small nuts and bolts in close corners, and at the same time gives a handle-head of sufficient strength for the wrench-heads of 25 larger sizes.

Another feature is the provision of an extension shank 41 at present in the form of a solid rod having a spindle 42 and ratchet 30 recesses 43 at one end and a spindle socket 44, spring-pressed ball 45, and ratchet teeth 46 at its opposite end. The handle-head and pawl operate on the spindle end of said shank, as will be obvious, and the spindle of 35 any wrench-head may be inserted into the socket 45 and connected to the shank by engagement of the teeth 46 in the recesses 19. This construction permits operation of any wrench-head from a remote point as is frequently desired.

It will be observed that the principles disclosed herein enable the production of a handle and wrench-heads of simple construction, requiring comparatively little machining and that the parts are so associated 45 as to enable the transmission of pressures through the ratchet construction in reverse directions with but minimum wear on the co-operating parts. Furthermore, the construction disclosed herein is especially well suited to the use of a series of wrench-heads 50 of different sizes and shapes, and also to the use of an extension shank for the purpose described.

55 It is believed that the foregoing conveys a clear understanding of the objects prefaced above, and while I have illustrated but a single working embodiment, it should be understood that changes might be made in 60 details of construction without departing from the spirit and scope of the invention as expressed in the appended claims.

I claim:

65 1. A ratchet wrench comprising a cylindrical wrench-head shaped at one end to fit

an object to be turned and at its opposite end to provide a concentric cylindrical spindle and a radial annular shoulder at the juncture of the spindle and wrench-head proper, said shoulder having circumferentially spaced ratchet teeth formed therein reaching radially substantially from the spindle to the periphery of the wrench-head proper, a handle having adjoining parallel bores in one end, one for rotatably receiving said spindle and the other a pawl, a cylindrical pawl supported in the second mentioned bore and having a diametrical tooth at one end adapted to engage ratchet teeth and a diametrical surface at its opposite end adapted by cooperation with a spring-pressed element to hold the pawl from rotative displacement from either of two operative positions, and a spring-pressed element shaped to fit said diametrical surface and bearing 80 thereagainst for yieldingly urging the pawl into engagement with the ratchet teeth and permitting the pawl to be manually moved rotatably in its bore to either of said operative positions. 90

2. A ratchet wrench comprising a cylindrical wrench-head shaped at one end to fit an object to be turned and at its opposite end to provide a concentric cylindrical spindle and a radial annular shoulder at the juncture of the spindle and wrench-head proper, said shoulder having circumferentially spaced ratchet teeth formed therein reaching radially substantially from the spindle to the periphery of the wrench-head proper, a handle having adjoining parallel bores in one end, one for rotatably receiving said spindle and the other a pawl, a cylindrical pawl supported in the second mentioned bore and having a diametrical tooth at one end adapted to engage the ratchet teeth and a diametrical ridge at its opposite end, and a flat spring attached at one end to the handle and shaped at its opposite end to fit said diametrical ridge for yieldingly preventing rotative displacement of the pawl and for urging the latter into engagement with the ratchet teeth, said spring permitting the pawl to be manually moved rotatably for reversing the position of its driving face. 110

3. A ratchet wrench comprising a cylindrical wrench-head shaped at one end to fit an object to be turned and at its opposite end to provide a concentric cylindrical spindle and a radial annular shoulder at the juncture of the spindle and wrench-head proper, said shoulder having circumferentially spaced ratchet teeth formed therein reaching radially substantially from the spindle to the periphery of the wrench-head proper, a handle having adjoining parallel bores in one end, one for rotatably receiving said spindle and the other a pawl, a cylindrical pawl slideable lengthwise and rotatable 120 125 130

in the second mentioned bore and having a diametrical tooth at one end adapted to engage the ratchet teeth, a spring-pressed element operative between the handle and pawl for yieldingly urging the latter into engagement with the ratchet teeth and shaped in its connection with the pawl for preventing rotative displacement of the latter but permitting it to be manually moved rotatably for reversing the position of its driving face, 10 and a finger fixed to and extending from the pawl and adapted to be manipulated for reversing the pawl.

JOHN E. ERICKSON.
